UNITED STATES PATENT OFFICE.

JOHN A. BRIGGS, OF PHILADELPHIA, PENNSYLVANIA, ASSIGNOR TO
SUSANNAH T. BRIGGS, OF SAME PLACE.

MAIL-BAG.

SPECIFICATION forming part of Letters Patent No. 313,050, dated March 3, 1885.

Application filed December 11, 1884. (No model.)

To all whom it may concern:

Be it known that I, JOHN A. BRIGGS, a citizen of the United States, residing at No. 4,450 Frankford Avenue, Philadelphia, in the county 5 of Philadelphia and State of Pennsylvania, have invented certain new and useful Improvements in Mail-Bags; and I hereby declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 The object of my invention is to provide a new and improved mail-bag with a new and original device for closing, fastening, and locking the mouth of the bag.

The invention consists in the construction 20 and combination of the several parts, as is hereinafter fully set forth and described.

The accompanying drawings contain four 25 different views, Figures 1, 2, 3, and 4, in which similar letters of reference indicate corresponding parts in all the figures.

Fig. 1 is a front view of my mail-bag closed, with the flap or cover strapped down in its place. Fig. 2 is also a front view of the same with the flap turned up, showing my improved 30 fastening device, the safety-strap passing through the slots, and the hasp, swivel-link, and padlock in their proper places, the bag being closed and locked. Fig. 3 is a sectional view on the line *a b*. Fig. 4 is a perspective 35 view of the mail-bag open, showing the vertical slots through the flap and mouth of bag, the safety-strap, the short strap, the metal link, and outer flap and strap.

The bag *G* has attached to the upper back 40 edge of the mouth a flap, *A*, which, when the bag is closed, is turned over the top and fastened by the strap *H* to the buckle *I*, Fig. 1. The safety-strap *C* is riveted to the flap *A'*, having at the end the swivel-hasp *E*. The 45 short strap *C'* is riveted to the back of the upper part of the bag *G*, and has on its end the metal link *D*, with slot *d*, through which passes the hasp *E* for the padlock *F*, Fig. 2. The slots *B* on the flap *A'* correspond with 50 similar slots, *B'*, on the back of the mouth of the bag *G*, and also with the slots *B'* on the

front of the mouth of the bag *G*, Fig. 4. The strap *C'*, hasp *E*, connected with metal link *D*, the safety-strap *C*, and edge of flap *A* are shown in Fig. 3. The flap *A'* is re-enforced by a strip of leather riveted to the inside face, and the mouth of the bag is strengthened in like manner. The slots passing through the flap and mouth of bag may be protected by metal facings. 55

The following is the manner in which the bag is closed and locked: The flap *A'* is turned down and the slots *B* are brought over to correspond with the slots *B'*, and also with the slots *B'* in the mouth of the bag *G*. The 60 safety-strap *C* is then passed through the slots alternately until the last slot to the left of the bag is reached, through which is passed the swivel-hasp *E*. The short strap *C'* is then brought round over the flap *A'*, the metal link 65 *D* connected with the hasp *E* through the slot in the end of the link, and the padlock *F* put on the hasp, thus securely locking the bag. The flap *A* is then turned down and fastened by the strap *H* to the buckle *I*, thus protecting the safety-strap, hasp, and padlock from 70 injury through rough handling or otherwise. 75

What I claim, and desire to secure by Letters Patent of the United States, is—

1. The combination of the flap *A'* and the 80 safety-strap *C*, provided with the swivel-hasp *E*, and riveted to the front edge of the inside flap, *A'*, attached to the mouth of the mail-bag *G*.

2. The combination of the mail-bag *G*, provided with slots *B'* and *B'*, outer flap, *A*, re-enforced with a leather strip on the inside face of said flap *A*, short strap *H*, and buckle *I*, flap *A'*, provided with vertical slots *B*, safety-strap *C*, swivel-hasp *E*, and padlock *F*, substantially as shown and described. 85

3. The mail-bag *G*, combined with the outer flap *A*, inner flap, *A'*, safety-strap *C*, swivel-link *E*, and short strap *H*, all substantially as set forth. 90

In testimony whereof I affix my signature in presence of two witnesses.

JOHN A. BRIGGS.
